UNITED STATES PATENT OFFICE

CARL A. FLOOD, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS

PIN TICKET

Application filed October 4, 1930. Serial No. 486,360.

This invention relates to a pin ticket of the type used in marking articles of merchandise for sale or the like. The ticket is constructed to be applied either manually or by machine and is formed to engage the head of the pin to prevent withdrawal of the pin from the ticket, as well as to conceal the point of the pin to prevent its accidental engagement with adjacent articles.

10 Prior constructions of tickets which protect the pin point have been arranged so that after attachment to an article subsequent steps, such as folding the ticket or securing the ticket in its completed form as by adhesive, are necessary. The present invention is designed to permit attachment of a ticket which is completely formed before attachment, avoiding the necessity of folding or securing after its attachment to the article.

15 It is customary to provide ticket attaching machines with two separate feeding mechanisms, one for a pin carrying strip, the other for a tag strip. One aspect of my invention is directed to a ticket strip which carries therewith a pin for each ticket in the strip, simplifying the mechanical features necessary in attaching the ticket to articles. In the event that the strip tickets are to be attached by hand, the pin or attaching means is directly associated with the ticket, and accordingly an auxiliary pin supply is unnecessary.

20 In accordance with my invention I provide a ticket, the pin point being received between the front and back surfaces of the ticket to conceal it and protect it from engagement with adjacent articles. I also find it desirable to provide an opening through a portion of the ticket on the face side, which may receive the head of the pin partially concealing it and materially aiding in holding the pin in its position and preventing its accidental withdrawal from the ticket.

25 With reference to the drawing:

Fig. 1 is a plan view of a ticket strip;

Fig. 2 is a section along the line 2—2 of Fig. 1;

Fig. 3 is a section along the line 3—3 of Fig. 1;

Fig. 4 is a section of the ticket showing the pin completely inserted in the position of its attachment to an article, showing a guide by which the pin is inserted and the head of the pin engaging the hole;

Fig. 5 is a plan view of a ticket attached to an article;

Fig. 6 is a plan view similar to Fig. 1 illustrating another form of ticket;

Fig. 7 is a section along the line 7—7 of Fig. 6;

Fig. 8 is a section along the line 8—8 of Fig. 6;

Fig. 9 is a section similar to Fig. 7 showing another modification of the ticket;

Fig. 10 is a section similar to Fig. 9 of the same modification, with the guide inserted to aid in attaching the pin;

Fig. 11 is a plan view of another modification of the ticket strip showing the structure for carrying the pin between the tickets;

Fig. 12 is a section along the line 12—12 of Fig. 11;

Fig. 13 is a plan view of another modification showing another way of carrying the pin in the ticket;

Fig. 14 is a section along the line 14—14 of Fig. 13;

Fig. 15 is a section through the point of the guide of Figs. 4 and 10 showing the groove in the underside of said guide; and

Fig. 16 is a section similar to Fig. 14 showing an additional modification.

Referring particularly to Figs. 1 to 5 inclusive, the ticket strip 1 is made up of a plurality of plies 2, 3 and 4 (Fig. 3), the back plies 3 and 4 being folded over to lie against the inner face of the front ply 2, having their adjacent edges contacting and secured to the ticket at points spaced from the fold, leaving flat tubular portions along either edge. The strip is notched at 5 and 6 at longitudinally spaced points to form individual tickets joined in the strip by short connecting portions 7. These short connecting portions may be cut away when the tickets are attached, leaving straight edges on all sides of the tickets. The notches also weaken the strip along the point between the strips, to aid in severing the tickets when attached by hand.

Fig. 1 is a plan view of a ticket strip;

Fig. 2 is a section along the line 2—2 of Fig. 1;

Fig. 3 is a section along the line 3—3 of Fig. 1;

Fig. 4 is a section of the ticket showing the pin completely inserted in the position of its attachment to an article, showing a guide by which the pin is inserted and the head of the pin engaging the hole;

Fig. 5 is a plan view of a ticket attached to an article;

Fig. 6 is a plan view similar to Fig. 1 illustrating another form of ticket;

Fig. 13 is a plan view of another modification showing another way of carrying the pin in the ticket;

Fig. 14 is a section along the line 14—14 of Fig. 13;

Fig. 15 is a section through the point of the guide of Figs. 4 and 10 showing the groove in the underside of said guide; and

Fig. 16 is a section similar to Fig. 14 showing an additional modification.

A pin 8 is carried between adjacent tickets, transversely of the strip, being inserted between the front and back plies, as shown in Fig. 2. In the front ply 2 of the ticket I provide an opening or perforation 9 which is adapted to receive the point of a guide member 10 for directing the point of the pin in between the two plies, as shown most clearly in Fig. 4. A grooved portion 11 (Fig. 15) of the guide acts to maintain the pin point in the desired direction, and direct it between the plies as desired. The guide is shown merely as an illustration and any guide means may be used instead. A second opening 12 adjacent to the fold edge is provided in the front ply, opening into one of the unsecured portions, to receive the head of the pin as disclosed in Fig. 5, and prevent its withdrawal from the ticket, the edges of the opening extending around and across the head and being engageable therewith as shown most clearly in Fig. 4.

With reference to Figs. 6, 7, and 8, the ticket strip 13 is made up of three plies, 14, 15, and 16, the back plies 15 and 16 being folded over to be superimposed one on the other and adjacent the front ply 14. In this modification the plies 15 and 16 are secured together throughout their surfaces, forming a flat tubular portion between front and back plies. As shown most clearly in Fig. 6, I provide a modified means for carrying the pin. The pin 18 is inserted transversely of the ticket between the plies 14 and 15. A notch 17 may, if desired, be provided in the edge of the ticket to receive the head of the pin and permit it to lie within the outer edge of the ticket, thus leaving no projections on the edge of the ticket strip. This ticket strip is notched at 19 and 20 as in the preceding modification, leaving short portions 22 similar to the portion 7 connecting the individual tickets in the strip. The openings 23 and 24 operate in the same manner as the openings 9 and 12 respectively of the preceding modification.

The modification of Figs. 9 and 10 is made up of two plies 25 and 26 folded upon each other and secured together over a greater part of their surface, leaving the portion adjacent the fold unsecured, forming a flat tubular portion to receive the head of the pin. The openings 27 and 28 in the front ply 25 have the same function as the openings 9 and 12 above described. The ticket strip is constructed in the manner of the strips of the preceding modifications. A guide member 10 is shown in Fig. 10 similar to the guide of Fig. 4.

In the modification of Figs. 11 and 12, the ticket is constructed similarly to the ticket of Figs. 9 and 10. This ticket has a front ply 33 and a back ply 34 folded upon each other and secured together as in the preceding modification, leaving a flat tubular portion adja-

cent the fold, the fold in this modification being at the edge concealing the pin point rather than at the edge adjacent the head end of the pin. This ticket is notched as in the preceding modifications, as at 35 and 36, and the pin 37 is carried between the individual tickets by inserting it back and forth through the tickets through holes 38 and 39, which may be formed before the pin is inserted, as by punching, or which the pin may form of itself as it is inserted. The openings 40 and 42 have the same function as the openings of the preceding modifications, and the portions connecting adjacent tickets may be removed when the tickets are attached as above set forth.

Figs. 13 and 14 show another modification in which the pin is carried longitudinally of the strip. In this modification a front ply 43 and a back ply 44 are folded upon each other and are secured together, the portion adjacent the fold of the front and back plies being left unsecured, as at 46, to form a flat tubular portion, the pin 47 being carried longitudinally in this tubular portion. The openings 48 and 49 in this modification, similar to openings 9 and 12, are arranged longitudinally of the strip, since it would be apparent that the holes must lie in the direction in which the pin is to be inserted. In each of the modifications, the back ply presents a backing for the openings in the front ply. These tickets have cut-out portions 50 and 52 similar to the cut-out portions of the preceding modifications, for indicating the individual tags.

The invention includes not only a folded over ticket but also a ticket formed by securing a plurality of separate plies together on their contacting surfaces, except for an unsecured portion between the edges forming a tubular portion. In Figs. 13 and 14, for example, instead of forming the ticket strip from a single sheet of paper folded at the upper edge, the strip may be formed of two pieces cemented together face to face throughout more or less of their juxtaposed areas about the openings 48 and/or 49 and the upper edges of the pieces as illustrated at 60 in Fig. 16. Thus it will be evident that the tubular space between the plies of the ticket may be defined on both sides either by folds of a single piece of material or by cementing together two pieces or the space may be defined on one side by a fold and on the other side by cementing the two plies together. Accordingly, the ticket may be defined as a plurality of plies secured together at transversely spaced points to form a tubular portion, or as a ticket having a plurality of plies secured together, at least two of said plies being unsecured over a small area between the edges of the tag, to receive a portion of the attaching pin.

Since one of the functions of the unsecured

tubular portion is to form a space between the plies of the ticket to receive the point and/or the head of the pin, it will be apparent that the portion of the tube spaced from either or both of the openings may be secured together. Thus in Fig. 14 or 16 the plies may be secured over their entire contacting surface except for a portion adjacent the openings 48 and/or 49.

10 From the foregoing it will be evident that the front and rear portions of the tag or ticket constitute "plies", whether they be secured or fastened together by a fold or by cement or in any other way, even though they be formed from a single piece of paper or the like.

15 Although it is common in single ply tickets to provide an opening for the head of a pin, nevertheless the head usually projects beyond the face of the ticket almost if not quite as much as though no opening were provided.

20 This is due to the fact that a ticket when pinned to an article normally assumes a convex shape so that the shank of the pin does not engage the ticket adjacent the opening and the head therefore extends into the opening little if any, and even if the ticket is maintained flat, as by bending the pin, less than half of the head can project into the

25 opening due to engagement of the shank of the pin with the ticket adjacent the opening. In my construction the multi-ply construction overcomes this for the portion of the

30 ply having the head receiving perforation is unsecured and normally spaced from the opposite ply to provide a recess which receives and encloses the head, this being assured by the arrangement of the fold adjacent the head receiving perforation so that the plies

35 may separate, and the material around the opening will obstruct removal of the pin head. The securing is more positive in a construction having the fold on the edge adjacent the pin, since, if the top layer rises above the pin,

40 the pin head can not be withdrawn past the fold edge.

45 It will be readily apparent that the structure of my invention described includes not only a plurality of openings in the front ply but also a ticket without openings in the front ply; for example, in the modification of Figs. 1 to 5 either or both of the openings 9 and 12 may be eliminated.

50 When both openings are omitted, the point of the guide will force itself through the material into the space between the front and back plies, and the pin point will form an opening at the point where the opening 12 will normally occur. Also only a single opening may be used

55 as for example merely the opening 9 to receive the point of the guide. In both of these latter forms the locking feature for retaining the pin in place would not be included in the ticket structure. However, a

60 satisfactory ticket may also be made having

merely the opening 12 for the head of the pin, the guide in this case breaking through the top ply due to its own pointed end. The locking feature for the head of the pin would then be found in such a modification.

65 It will be apparent that many advantages of the constructions illustrated may be obtained by modifying a ticket such as that shown in Fig. 1, for example, by cutting away the portion of the perforated ply so as to 70 form a slot connecting the openings 9 and 12, or the latter openings may be replaced entirely by a transversely extending slot of these proportions, or, if desired, by a slit through which the pin may be passed at transversely spaced points. It will be evident that when arranged in this manner a slot would function in much the same way as the openings 9 and 12 while a slit may likewise be arranged to function in a somewhat similar 75 manner.

80 The ticket is attached to an article as shown by way of example in Fig. 4 by inserting the pin back and forth through at least the rear 85 ply of the tag, and leaving the point of the pin between the two plies. In order to more readily cause the point of the pin to remain between the plies I direct it therebetween by means of a guide, which is adapted to be inserted into the tag in such a manner as to 90 engage the point of the pin as it is being forced through the tag, and cause it to be directed between the plies. This may be done in any desired manner, as by inserting it 95 through the tubular portion. The guide is 100 shown in Fig. 4 as inserted through an opening in the face of the tag adjacent the point of the pin. The opening through which the guide is inserted locates the guide member in its desired position, and as the pin is forced 105 through the ticket it engages the surface of the guide and follows along the groove of the guide so that the point is directed between the plies, the groove preventing the pin point 110 from sliding off the guide surface. The same 115 method of attachment may be used in all the modifications. In tickets having no opening for the guide, an opening is formed by the 120 guide point as it is forced into the tag.

125 When the plies are secured together adjacent the hole for the guide, as in Fig. 9, the point of the guide forces its way between the plies and separates them to some extent, forming an opening into which the point of the pin is forced. Upon withdrawal of the 130 guide the front ply, which has been forced away from the back ply by the guide, will 135 return to its original position.

140 Since the pins are carried between the tickets, or between the plies of the tickets, previous to attachment of the ticket to an article the tag face is not mutilated, but is left smooth for printing or other marking.

145 The pin is inserted into the ticket in attaching an article thereto by inserting the

point of the guide between the plies of the ticket and then inserting the point of the pin into the opening which receives the head, or, if there is no opening for the head, into 5 that portion of the front ply against which the head is finally to be disposed. The pin is directed down through the tag to engage the material to which the tag is to be attached, and returned to pass through the 10 rear ply of the ticket again and is then directed by the guide into the space between the plies of the ticket. Obviously the ticket must be bent as shown in Fig. 4 to permit the pin to remain straight. It will be apparent that 15 the pin point may return through the top ply before it engages the guide, but it may then be directed back through the top ply by the guide and into its protecting space as desired. This is dependent upon the construction and operation of the guide means. The pin is inserted until the head is received by the opening as shown in Figs. 4 and 5. From this position removal is made somewhat difficult, as will be apparent, the mode 20 of attachment being similar in all cases. In the first modification discussed the pin extends transversely of the tube, in the last modification it extends longitudinally.

Accordingly I provide a preformed or 30 made-up ticket, that is, a ticket which is completely formed before its attachment to an article, avoiding any further operation on the ticket after it has been attached. This ticket is a multi-ply ticket forming a front 35 ply and at least one back ply, portions of which plies are preferably unsecured to provide a flat tubular portion which receives a portion of the pin. I may also provide, as desired, one or more openings in one of the 40 plies to receive either the point of a guide, or the head of a pin, or both. I also provide a ticket strip construction which carries therewith pins used in attaching the ticket to articles. These pins are carried at spaced 45 points, the spacing of the pins corresponding with the spacings of the individual tickets in the ticket strip, to provide a pin for each individual ticket.

I also provide a ticket strip made up of 50 a plurality of plies having a series of perforations in one of the plies, the plies being secured together on opposite sides of the perforations, as for example in Fig. 3, the plies are secured on opposite sides of the 55 series 9 and also the series 12. This is however not necessarily true of each set of perforations, since, for example, it is conceivable that the plies of Fig. 9 may be unsecured from the opening 27 to the edges of 60 the tag.

It should be understood that the present disclosure is for the purpose of illustration only and that this invention includes all modifications and equivalents which fall 65 within the scope of the appended claims.

For example, the method herein claimed may be practiced not only by hand but also by machines, two of which are disclosed and claimed in my copending applications Serial No. 565,466, filed September 28, 1931, and 70 Serial No. 657,233, filed February 17, 1933.

I claim:

1. As an article of manufacture a made-up pin-ticket comprising a plurality of plies secured together to form a flat tubular member to be attached to an article, one of the plies having an opening disposed to receive and to hold a pin with an end portion of the latter disposed transversely within the flat tubular member. 75
2. A made-up ticket comprising a plurality of layers formed by folding a strip of material upon itself, said layers being unsecured adjacent one fold edge and an opening in the top layer spaced adjacent to said fold edge. 85
3. A ticket strip comprising a flat tubular member to form individual tags and pins detachably carried thereby at evenly spaced points, said pins providing means for securing the tag to the desired material. 90
4. A ticket strip comprising a strip of material having spaced weakened portions defining individual tags, and pins carried by the strip having the same spacing as the weakened portions. 95
5. A ticket strip comprising a flat tubular strip of material having spaced portions defining individual tags, and pins carried by the strip having the same spacing as the spaced portions. 100
6. A ticket strip comprising a strip having longitudinally spaced openings in its face, and pins carried by the strip spaced apart a distance equal to the spacing of the openings. 105
7. A ticket strip comprising a strip of material having longitudinally spaced weakened portions formed by slits at either side of the tag, and a pin carried by each said weakened portion. 110
8. A ticket strip for tag attaching machines comprising longitudinally spaced tags adapted to be attached to articles and pin-carrying connecting portions, said portions being adapted to be removed upon attachment of the tag. 115
9. In combination a made-up tag comprising a flat tubular member and a pin extending through one wall of the member engageable with material to which the tag is secured, the point of the pin being retained in and concealed by the tube. 120
10. A ticket strip for machine attachment to articles comprising a strip folded longitudinally upon itself to form a plurality of plies, spaced openings in the uppermost ply and spaced within the outer edges of the strip, and weakened portions equally spaced to define individual tickets, certain of the plies being secured together to form a flat tubular member. 125

11. As an article of manufacture a made-up ticket comprising integral front and back plies formed by folding a strip of material upon itself, the opposite edges being fold edges, some of said plies being secured together to form a flat tubular portion, and an opening in the top layer adjacent one end of the tubular portion, whereby an attaching pin may have an end portion thereof disposed in this opening so as to be protected by the adjacent fold edge. 5
12. A preformed pin-ticket for fabric and other articles, at least a portion of which comprises a plurality of plies one of which is 10 perforated, the plies being interconnected throughout a portion of their opposing faces before the ticket is pinned to the article, the ply adjacent the perforate ply overlying the perforate portion thereof and being unconnected thereto in the immediate vicinity of said perforate portion, whereby the latter plies may be freely separable in the immediate vicinity of such perforate portion to receive and protect the end portion of a pin. 15
13. A strip of pin-tickets separable from each other for individual attachment to articles comprising superposed layers, one layer having longitudinal rows of perforations within its edges and being interconnected with another layer on opposite sides of each perforation of said rows. 20
14. In combination with a sheet of material, a made-up tag comprising front and rear plies secured together with an opening in the 25 front ply and a pin extending through the tag, thence through said material, thence through the rear ply at said opening and thence between the two plies so that the point of the pin is enclosed. 30
15. In combination a made-up tag comprising front and rear plies with spaced openings in the front ply, and a pin extending through one of said openings, thence through the rear ply, thence through the material to 35 which the tag is secured, thence through the rear ply, and finally between the two plies to a point spaced from the second opening, whereby the head of the pin may be received in the first opening and the point of the pin 40 may be enclosed between the plies. 45
16. In combination with a sheet of material, a made-up tag comprising a plurality of layers, one of which is perforated and the other of which presents a surface at the back 50 of said perforation, and a pin extending through the perforation and said other layer into the sheet of material and thence through the latter layer and between the layers for a sufficient distance so that the point is enclosed 55 and the head is disposed in said perforation, whereby the perforation may be effective for preventing unintentional removal of the pin. 60
17. In combination with a sheet of material, a made-up tag comprising a plurality of layers, one of which is perforated and the 65 other of which presents a surface at the back of the perforation, and a pin extending through the layers and into the sheet of material, thence through the adjacent layer, and finally between the layers beyond the perforation so that the point is enclosed, the pin being straight from the tip to the tag-piercing portions thereof, whereby the pin may be easily removed. 70
18. In combination with a sheet of material, a made-up tag comprising front and rear plies with a preformed opening in the front 75 ply and a pin extending through the tag on one side of the opening, thence through said material, thence through the rear ply, and subsequently between the two plies at the other side of the opening so that the point of the pin is enclosed. 80
19. In combination with a sheet of material, a made-up tag comprising front and rear plies with a preformed opening in the front 85 ply and a pin extending through the tag on one side of the opening, thence through said material, thence through both plies on the same side of the opening, thence through the opening and thence between the two plies on the other side of the opening so that the point of the pin is enclosed. 90
20. In combination with a sheet of material, a tag comprising front and rear sheet 95 portions, a pin extending through both portions, thence through said material, thence through the rear portion only, and thence between the two portions. 100
21. In combination with a sheet of material, a tag comprising front and rear sheet portions, a pin extending through the tag, thence through said material, thence through both portions, thence through the front portion only, and thence between the two portions. 105
22. In combination with a sheet of material, a tag folded to form front and rear portions, a pin extending through both portions, thence through said material, thence through the rear portion only and thence between the two portions. 110
23. In combination with a sheet of material, a tag folded to form front and rear portions, a pin extending through the tag, thence 115 through said material, thence through both said portions, thence through the front only, and thence between the two portions.
24. A ticket strip comprising integrally joined ticket portions for separation and individual attachment, the strip being folded longitudinally to form a plurality of plies and having an opening in one ply of each ticket portion at a point spaced from the longitudinal fold, the plies being secured together on the side of the openings opposite the fold. 120
25. An elongate strip of material for making pin tickets, characterized in that the strip is folded longitudinally, the two sides 125

being cemented together with an uncemented space adjacent the fold line, one side of the strip having a series of pin-guide openings spaced from the fold line and communicating with said space, the openings being spaced longitudinally of the strip at the same intervals as those at which the strip is to be severed to form the individual tickets.

26. The method of pinning to an article a ticket having an opening extending partially through the ticket from one side thereof, which comprises holding the ticket and article in juxtaposition, inserting a pin through the ticket and article, and then inserting the point of the pin through said opening to a position between the opposite faces of the ticket.

27. The method of pinning to an article a ticket having an opening extending partially through the ticket from one side thereof, which comprises holding the ticket and article in juxtaposition, inserting a pin through the ticket and article, the pin entering the ticket from said side at a point remote from the opening and emerging from said side at a point intermediate said point and opening, and then inserting the point of the pin through said opening to a position between the opposite faces of the ticket.

30. Signed by me at Framingham, Massachusetts this second day of October, 1930.

CARL A. FLOOD.
